UNITED STATES PATENT OFFICE.

THEODORE WEISS, OF CHICAGO, ILLINOIS.

ELECTRICAL SIGNALING DEVICE.

1,029,521.

Specification of Letters Patent. Patented June 11, 1912.

Application filed March 18, 1911. Serial No. 614,943.

To all whom it may concern:

Be it known that I, THEODORE WEISS, a citizen of the United States, and resident of Chicago, county of Cook, and State of Illinois, have invented certain new and useful Improvements in Electrical Signaling Devices, of which the following is a specification, and which are illustrated in the accompanying drawings, forming a part 10 thereof.

The invention relates to devices for giving a warning signal, and is primarily intended for the use of automobile drivers.

The object of the invention is to provide 15 a simple but powerful warning signal; and it consists of an electric motor, associated with a diaphragm, with special means, as hereinafter described, for actuating a tapper for rapidly striking the diaphragm 20 to produce the desired sound.

The invention is illustrated in the accompanying drawings, in which—

Figure 1 is a side elevation of the complete device; Fig. 2 is a detail section 25 through the casing carrying the diaphragm and showing the tapping mechanism; Fig. 3 is a detail in perspective of the tapping device, some of the parts being broken away; and Fig. 4 is a sectional view on the 30 line 4—4 of Fig. 2.

A rotary electric motor 10, of any suitable construction, is carried by a bracket arm 11, adapted for attachment to an appurtenance, such as the dashboard of an automobile, or other suitable support. A chambered casing 12 is secured to the body of the motor 10 by means of a collar 13, to which the casing is suitably attached, as by means of arms 14, 15. A diaphragm 16, preferably of metal, is secured within the casing 12, in a position perpendicular to the shaft 17 of the motor, the center of the diaphragm being preferably in line with the axis of the shaft. A tapper or hammer 18 is sleeved upon the outer end of the shaft 17, and is free to move longitudinally thereupon. The tapper normally lies out of contact with the diaphragm, but is sufficiently close thereto so that it may be thrown forcibly against its face. A pair of rigid arms 19, 20, extend backwardly from the tapper 18, and are inclined outwardly, and at their inner ends are provided with eyes loosely encircling a pair of arms 21, 22, pivoted to 45 and projecting radially from a collar 23 fixed upon the shaft 17. A plurality of

cams 24, 25, which are preferably V-shaped, are secured to the inner wall 26 of the casing 12 and project into the path of the arms 21, 22 forcing them forward and thus 50 throwing the tapper 18 against the diaphragm. Preferably the cams are located upon opposite sides of the shaft in order that they may simultaneously engage both of the arms. The high speed of the motor 55 causes the arms to resume their normal position as perpendicular to the shaft by centrifugal force as soon as they are released from the cams, thus withdrawing the tapper. By this means the tapper is thrown 70 forcibly against the diaphragm at each revolution of the motor shaft. Obviously by introducing additional cams, preferably in pairs, the tapping action becomes more rapid.

The diaphragm 16 is held against a shoulder at the forward end of the casing 12, by means of a cap 28 engaging the end of the casing. Preferably soft gaskets 29, 30, which may be of cardboard or similar material, are applied to the opposite faces of the diaphragm, and there may be interposed between the inner gasket 29 and the shoulder of the casing a ring 27 and an annulus 33, the latter having an instanding or radial 85 and a peripheral flange, thereby constituting a cup within which the ring is inclosed. The cap 28 has a central aperture which forms the throat of a resonating horn 31. A collar 32 is fixed upon the shaft 17, and 90 projects through and turns in a central aperture in the rear wall 26 of the casing 12.

While the motor is shown arranged with its shaft perpendicular to the diaphragm, and this construction is preferred because 95 of its simplicity, I do not desire to be limited to this arrangement, but regard my invention sufficiently broad to include any arrangement of motor which will secure the rotation of the tapper-advancing mechanism shown. Indeed, the scope of the invention is sufficient to include any other form of motor than electrical, it being necessary only that the shaft carrying the advancing arms be given a rapid rotation.

The cams 24, 25, are preferably V-shaped to permit the shaft to be rotated in either direction, so that a reversible motor may be employed.

I claim as my invention—

1. In a signaling device, in combination, a diaphragm, a tapper located adjacent the

diaphragm, a rotatable head, arms projecting radially from the head and pivoted to swing in a plane coincident with the axis thereof, bars connecting the arms with the tapper, and means for swinging the arms on their pivots.

2. In a signaling device, in combination, a diaphragm, a tapper located adjacent the diaphragm, a rotatable head, arms projecting radially from the head and pivoted to swing in a plane coincident with the axis thereof, bars connecting the arms with the tapper, means for swinging the arms on their pivots, and an electric motor for rotating the head.

3. In a signaling device, in combination, a chambered casing having an apertured end, a diaphragm secured within the casing, a shaft journaled in the opposite end of the casing, a tapper slidably mounted on the end of the shaft and adapted to strike the diaphragm as it reciprocates, a head fixed to the shaft, arms radiating from the head and pivoted thereto to swing in a plane coincident with the axis of the shaft, bars connecting the arms with the tapper, and cams fixed to the casing and entering the path of rotation of the arms.

4. In a signaling device, in combination, a chambered casing having an apertured end, a diaphragm secured within the casing, a shaft journaled in the opposite end of the casing, a tapper slidably mounted on the end of the shaft and adapted to strike the diaphragm as it reciprocates, a head fixed to the shaft, arms radiating from the head and pivoted thereto to swing in a plane coincident with the axis of the shaft, bars connecting the arms with the tapper, cams fixed to the casing and entering the path of rotation of the arms, and an electric motor for driving the shaft.

5. In a signaling device, in combination, a rotary electric motor, a casing secured to the motor, the end of the motor shaft projecting into the casing, a diaphragm mount-

ed within the casing and being perpendicular to the axis of the shaft, a tapper slidably mounted on the end of the shaft and adapted to strike the diaphragm, a pair of arms radiating from the shaft and pivoted to swing in a plane coincident with the axis thereof, connection between the arms and the tapper, and cams fixed within the casing and projecting into the path of rotation of the arms.

6. In a signaling device, in combination, a rotary electric motor, a casing secured to the motor, the end of the motor shaft projecting into the casing, a diaphragm mounted within the casing and being perpendicular to the axis of the shaft, a tapper slidably mounted on the end of the shaft and adapted to strike the diaphragm, a pair of arms radiating from the shaft and pivoted to swing in a plane coincident with the axis thereof, connection between the arms and the tapper, and V-shaped cams fixed within the casing and projecting into the path of rotation of the arms.

7. In a signaling device, in combination, a diaphragm, an arm mounted to rotate about an axis perpendicular to the diaphragm and to swing toward and away from the diaphragm, a tapper for striking the diaphragm actuated by the arm, and a cam projecting into the path of rotation of the arm.

8. In a signaling device, in combination, a diaphragm, a tapper located adjacent the diaphragm and impinging directly thereon, a head rotatable about an axis perpendicular to the diaphragm, an arm projecting radially from the head and being oscillatable in a plane coincident with the axis thereof and acting upon the tapper to force it against the diaphragm, and means for causing the movement of the arm.

THEODORE WEISS.
